UNITED STATES PATENT OFFICE.

WILLIAM L. MCCOMB, OF WINDOM, MINNESOTA, ASSIGNOR OF ONE-THIRD
TO J. EDWARD JOHNSON, OF WINDOM, MINNESOTA.

FOLDING UMBRELLA.

SPECIFICATION forming part of Letters Patent No. 739,437, dated September 22, 1903.

Application filed December 18, 1902. Serial No. 135,720. (No model.)

To all whom it may concern:

Be it known that I, WILLIAM L. MCCOMB, a citizen of the United States, residing at Windom, in the county of Cottonwood and State of Minnesota, have invented certain new and useful Improvements in Folding Umbrellas; and I do hereby declare the following to be a full, clear, and exact description of the invention, such as will enable others skilled in the art to which it appertains to make and use the same.

This invention relates to umbrellas and contemplates an improved construction by which an umbrella may be folded into approximately one-half of its usual compass, the construction including, among other features, novel means for locking the rib-joints when the ribs are in extended condition and also novel means for pivotally connecting the ribs and stretchers, respectively, to the stick and runner.

The details of construction are fully set forth in the following description, which is to be read in connection with the accompanying drawings, in which—

Figure 1 is a view in elevation of the stick and one rib and stretcher embodying the improvements. Fig. 2 is an enlarged elevation, and Fig. 3 an enlarged sectional view, showing the pivotal connection of a rib with the stick. Fig. 4 is an enlarged elevation, and Fig. 5 an enlarged sectional view, showing the pivotal connection of a stretcher with the runner. Fig. 6 is an enlarged elevation of a portion of a rib and stretcher, the extended and folded conditions of the rib being respectively shown in full and dotted lines. Fig. 7 is a further enlarged sectional view on line 77 of Fig. 6.

Referring to the drawings by numerals, 1 denotes the stick, which is in two sections, united by the screw-joint, (shown at 2.) The ribs are each composed of an inner section 3 and an outer section 4, the inner sections being pivoted to the stick by the following means: Encircling the stick is a sleeve having an upper portion 5, closely fitting the stick and which may have a lateral hole 6 for the insertion of a pin for fastening the sleeve to the stick and a lower enlarged portion 7, having in its wall a plurality of vertical slots 8, cor-

responding in number to the number of ribs employed. The enlarged portion 7 is chambered to provide room for heads on the rib-sections 3, which heads are formed by cutting away the metal at opposite sides, as shown at 9. The ribs at the reduced portion are of slightly less width than the width of the slots 8, which they occupy, and the heads, by engaging the inner wall of the enlarged portion, 55 prevent the withdrawal of the ribs, but allow free movement thereof in the opening and closing of the umbrella. In assemblage the rib ends are inserted in the slots and the sleeve is slipped over the stick at its upper 60 end, the stick thus aiding to confine the rib ends. The sleeve may be secured by means of the pin above mentioned or by a stop 10 on the stick and a cap-sleeve 11. The runner consists of a sleeve 12, having toward its upper end an annular flange 13, integral with the sleeve and of angular form in cross-section. The flange is provided with vertical slots 14, corresponding in number to the number of stretchers 15, the latter being provided with heads 16, formed by cutting away the metal in a manner similar to that described with reference to the rib ends. The runner-sleeve is exteriorly threaded below the flange, and 17 is a nut engaging the threads 70 and screwed against the base of the flange to confine the stretcher ends which occupy the slots. The flange extends beyond the runner-sleeve a sufficient distance to freely accommodate the heads on the stretchers. 75

The nut 17 is provided at its upper end with an annular depression 17', receiving the lower end of the flange 13. The threaded bore of the nut is of sufficient diameter to allow it to be slipped over the flange at the bottom of 80 the sleeve 12.

The inner and outer rib-sections 3 4 are joined together to permit of folding, the outer sections 4 being each provided near its outer end with ears 18, to which is pivoted the reduced inner end 19 of the inner section. Said end 19 is offset to bring the rib-sections into alinement when unfolded. The end of each rib-section 4 is split and is of T form, providing lower ears 20, to which is pivoted 95 the outer end of a stretcher, and providing a spring-clamp 21, the jaws of which extend up- 100

wardly from the rib-section end or in a direction opposite to that of the ears 20 and which conform at their inner faces to the inner rib-section which they engage, and preferably 5 said inner rib-sections are of round form in cross-section. The clamp holds the outer rib-section in alinement with the inner rib-section when said sections are unfolded; but the engagement being frictional a slight pressure will release the held section and permit 10 folding.

The umbrella is foldable when in closed condition, and as the joints are about midway of the length of the ribs the compass of the umbrella is reduced by folding to about one-half. 15 The stick is, as before stated, in two parts, which are disconnected when the umbrella is in folded condition.

I claim as my invention—
20 1. A folding umbrella having ribs each formed of sections pivoted together to be in alinement when unfolded, ears on one of the sections for pivotal connection with a stretcher, and spring-jaws extending from the 25 said section in the same plane but oppositely from said ears to clamp the other section when unfolded.

2. A folding umbrella having ribs each

formed of sections the inner one of which has a reduced upturned end, and the outer section having at its upper side two ears to which 30 said apertured end is pivoted, and having an integral split end from which extend upwardly clamping-jaws for the inner section and from which extend downwardly ears for 35 connection with the stretcher, said jaws and downwardly-extending ears being in the same vertical plane.

3. In a folding umbrella, a sleeve having toward its upper end an integral annular flange 40 of inverted-L form in cross-section provided with radial slots, and having below said flange external screw-threads, headed members occupying said slots, and a nut engaging said threads and having at its upper end an annular depression receiving the lower end of said flange and serving with said slots to confine 45 said members, the lower end of the flange shouldering against the wall of the depression.

In testimony whereof I affix my signature in presence of two witnesses.

WILLIAM L. MCCOMB.
